SEARCHED

ATTORNEY

UNITED STATES PATENT OFFICE.

ALVA DEERWESTER, OF BUTLER, MISSOURI.

SAFETY CATCH FOR ELEVATORS.

Application filed July 6, 1923. Serial No. 649,935.

To all whom it may concern:

Be it known that I, ALVA DEERWESTER, a citizen of the United States, residing at Butler, in the county of Bates and State 5 of Missouri, have invented new and useful Improvements in Safety Catches for Elevators, of which the following is a specification.

This invention relates to elevators or 10 mine cars used for elevator purposes and has for its object the provision of a novel catch device which will automatically operate to catch and hold the elevator against dropping in case of breakage of the cable or 15 the hoisting mechanism.

An important object is the provision of a 20 device of this character which is entirely inactive while the elevator structure is in normal or proper condition but which acts instantaneously to exert its catching and holding action in case of derangement of the hoisting machinery.

Another object is the provision of a device 25 of this character which will be simple and inexpensive to manufacture and install, simple in its operation, positive in action, efficient and durable in service and a general improvement in the art.

With the above and other objects and advantages in view the invention consists in 30 the details of construction to be hereinafter more fully described and claimed and illustrated in the accompanying drawings, in which:

Figure 1 is a vertical section through an 35 elevator or mine shaft showing the elevator and illustrating the catch mechanism in its normal position,

Figure 2 is a similar view showing the 40 cable broken and the parts in their holding position,

Figure 3 is a longitudinal sectional view 45 on a considerably larger scale,

Figure 4 is a detail cross section at right angles to Figure 3 the view being taken on the line 4-4 of Figure 3,

Figure 5 is a vertical section on the line 5-5 of Figure 3,

Figure 6 is a detail perspective view of 50 one of the catch members.

Referring more particularly to the drawings the letter A designates an elevator shaft or mine shaft against the sides of which I secure upright guides 10 which may be formed of angle bars, beams or any other 55 similar structural elements and which have

their confronting faces formed or equipped with retaining teeth 11 of a ratchet like nature including inclined walls 12 and square shoulders 13.

The car or elevator B is moved by means of the usual cable C wound in or let out by the usual or any preferred hoisting mechanism. Secured upon the top of the car B is a frame structure 14 having a suitable hole or guide 60 15 through which the cable passes, and including laterally extending guides 16. Slidable through these guides are plungers 17 which have their outer ends carrying heads 18 formed with beveled ends 19 for co-operation with the ratchet like teeth 11. The inner ends of these plungers project inwardly of the frame 14 and the plungers are normally urged outwardly by coil springs 20 which surround the plungers and which abut 70 75 against the heads 18 and shoulders 21 on the frame.

Mounted within the upper portion of the frame 14 is a laminated spring 22 which has its ends bearing against the underside of 80 the frame and which is normally bowed downwardly at its center. Encircling the central portion of the spring is a loop like yoke 23 to which the cable is attached by the means to be described. For supporting, 85 bracing and guiding the spring in its flexing movement, I provide elongated loop like guides 24 which depend from the frame 14 and through which the spring passes. Pivoted on brackets 25 on the inside of the central arched portion of the frame 14 are angle levers 26 which have their lower arms pivotally connected at 27 with the inner 90 ends of the plungers 17. Of necessity this connection must be of the pin and slot type 95 to prevent binding. The upper arms of these angle levers are pivotally connected at 28 with links 29 which are pivoted at 30 on a bracket 31 which depends from the yoke 23.

While it is conceivable that various means might be provided for attaching the cable to the device, it is preferable that the cable be brought through a hole 32 in the top of the yoke 23 and that use be made of a filler block 33 fitting within the yoke 23 above the spring 22. This filler block is formed with a tapered opening 34 which receives the lower end of the hoisting cable C. In connecting the cable, the lower end thereof is raveled out or frizzled where it is disposed within the opening 34, and Babbit metal is 100 105 110

then poured into this tapered opening so as to mold about the raveled out end of the cable and provide a solid cone shaped mass 35 which will positively anchor the cable 5 within the block.

In the operation it will be seen that ordinarily the weight is borne by the block 33 and yoke 23 and the spring is flexed upwardly to a sufficient extent that the angle 10 levers are in such position that the plungers 17 and heads 18 carried thereby are out of engagement with the teeth 11 on the guides. In case of breakage of the cable, the strain on the spring 22 will be relieved 15 and this spring will bow downwardly, moving the angle levers 26 in such a way that the lower ends thereof will force the plungers outwardly until the heads 18 thereof engage the teeth 11. This will naturally 20 result in catching and holding the elevator so that it cannot drop and cause injury to the occupants.

From the foregoing description and a study of the drawings it will be apparent 25 that I have thus provided a simply constructed and easily installed safety device which will be inexpensive to make and positive in its action. Owing to the fewness of the parts and the simplicity of the entire 30 mechanism it is apparent that there is very little to get out of order so that the device should have a long life and satisfactorily perform all of its functions.

While I have shown and described the 35 preferred embodiment of the invention it is of course to be understood that I reserve the right to make such changes in the form, construction and arrangement of parts as will not depart from the spirit of the invention or the scope of the subjoined claims.

Having thus described my invention I claim:

1. A safety device for elevators comprising the combination with an elevator of a frame at the top thereof, said frame being 45 of arch shape and including oppositely extending tubular guides, outwardly sprung pressed plungers slidable within said guides, angle levers pivoted at their angles at the inside of the arch portion and having depending arms having slot and pin connection with the inner ends of the plungers, the top of the arch having an opening, the hoisting cable extending through said opening, a leaf spring within the arch and engaging thereagainst, retaining guide brackets of loop like formation on the arch portion straddling the spring, a head carried by the lower end of the cable and located within said arch portion, said spring extending through and being rigidly carried by said head, and a link pivotally connected with the head and with the inner ends of said angle levers. 50

2. In an elevator mounting, including a 55 frame on the elevator, means for connecting the hoisting cable to the frame comprising a head of open frame like construction, a spring device within the head engaging the elevator frame, the elevator 60 frame and the top of the head having openings for the passage of the cable, the lower end of the cable being frizzled out within the head, and a mass of metal within the head embedding the frizzled out end of 75 the cable.

In testimony whereof I affix my signature.

ALVA DEERWESTER.
